UNITED STATES PATENT OFFICE.

WILLIAM L. DENIO, OF ROCHESTER, NEW YORK, ASSIGNOR OF TWO-THIRDS
TO DANIEL B. PLATT AND HERBERT L. BUSHNELL, OF SAME PLACE.

MAGNETO-GENERATOR FOR FIRE-ALARM CIRCUITS.

SPECIFICATION forming part of Letters Patent No. 394,839, dated December 18, 1888.

Application filed July 13, 1888. Serial No. 279,803. (No model.)

To all whom it may concern:

Be it known that I, WILLIAM L. DENIO, of Rochester, in the county of Monroe and State of New York, have invented certain new and useful Improvements in Magneto-Generators for Fire-Alarm Circuits; and I do hereby declare the following to be a full, clear, and exact description of the same, reference being had to the accompanying drawings, forming a part of this specification, and to the figures and letters of reference marked thereon.

My present invention has for its object to provide an improved apparatus for use in connection with a fire-alarm or in any position to indicate an abnormal increase in the temperature, and more particularly to dispense with the use of a charged main line and the batteries usually employed in such connections, thus decreasing the liability of a false signal being sent by the running down of the battery of a closed circuit or the failure to send a signal from the same cause if an open circuit is employed; and to this end it consists in providing instead of a battery a magneto-generator of novel construction so arranged and constructed that a current is generated and flows over the line upon the release of the motor operating the generator, and when said generator is inoperative the main line is closed and shunted around the generator-armature, materially decreasing the resistance of the circuit; and it further consists of certain novelties of construction and combination of parts, all as will hereinafter be fully described and claimed.

In the drawings, Figure 1 is a perspective view of a generator constructed in accordance with my invention; Fig. 2 a top plan view of the same, and Fig. 3 a vertical section.

Similar letters of reference in the several figures indicate similar points.

A represents a suitable base, upon which the generator is mounted, B representing the field-magnets and C the pole-pieces connected to the ends of said magnets, as ordinarily. Extending between these pole-pieces and connecting them are plates D D', having bearings formed on them, in which the ends of the armature-shaft are journaled.

The armature E is constructed of the well-known Siemen's type, having preferably two coils, E', thereon connected in series, the for-

ward end being extended, as shown at E², to form one end of the shaft, the other end being formed by a rod, E³, preferably of hard rubber or similar non-conducting material, passing through the rear bearing in plate D'.

In the plate D, in which the extension E² is journaled, is placed a bushing of hard rubber or similar material, in which said extension runs. By thus providing rubber or similar non-oxidizable bearings the perfect operation of it at all times will be insured, and there will be no liability of its sticking by reason of oxidization or from other causes, but its free operation is at all times insured. Further, a bearing is provided needing little or no lubrication; hence the liability of sticking by reason of gummed oil is obviated.

G represents a spring, one end being preferably secured to one of the pole-pieces or connecting-plates and the other to the armature or the forward extension of its shaft, operating, when wound up and released, to turn the armature a few times, the number of course depending upon the amount of the compression of the spring. This spring also preferably forms an electrical connection between the armature and the magnets; but it may, if desired, be insulated from one or both and the connection formed in another way.

The forward end of extension E² is provided with an arm, e, extending from its periphery and preferably projecting near the base of the instrument arranged to co-operate with a small lever, H, pivoted at h upon the base, and so arranged that when turned in one direction on its pivot one of its arms—preferably the shorter one—will engage the end of arm e and prevent the armature rotating, the other arm being preferably slotted at i, as shown. Mounted upon the base and preferably in proximity to the longer arm of lever H is an extension, I, provided at its outer end with a slot, j, corresponding to that in lever H, and in the slots i and j, and extending between these arms, is adapted to be placed a connecting-link, J, preferably constructed in two parts with the ends bent over, as shown, to engage the outer sides of the slotted portions and prevent their separation. The parts of the link are connected by solder, k, fusible at a comparatively low degree of heat—say, 150° Fahrenheit—but, if desired,

the link could be made of this material, cast or formed with lugs on the ends corresponding to the bent-over portions. It will be seen that upon the separation of the two parts of 5 the link the lever H can be turned on its pivot out of the path of the arm e, permitting the free rotation of the armature-shaft.

One terminal of the coils of the armature is 10 preferably connected to the metal of the armature-core or the spring; but the other is connected with the lateral extension m of the rod l, extending through the rod E³ in the armature, where it makes contact with a contact, n, carried upon a spring-finger, M, 15 secured to the base, as shown. This finger presses toward the rod E³, and the point n is preferably composed of carbon or similar non-oxidizable material, so that a good contact will always be maintained between them.

20 The electrical connections are fully shown in the plan view.

N N' represent binding-posts mounted on the base, with which the line-wires of the circuit are connected. From the post N' a conductor, 2, extends directly to the field-magnet pole-pieces, while from the post N a conductor, 5, extends to the post J on the base, and another, 3, extends to and is connected with the spring-finger M.

25 When the apparatus is in position for operation, the armature-spring is wound up and under tension, the arm E is engaged by one end of the lever H, and its other arm is connected with the post I by the link J. In this position there are two complete circuits passing 30 through the instrument, one starting at post N', extending to the pole-pieces of the magnet, through the spring G to the armature-body, through the armature-coils, rods l and m, contact n, spring M, and wire 3 to post N, and this circuit by reason of the fine wire of the armature is of high resistance. The other circuit starts at post N', passes to magnet pole-piece to armature-body, extension E², 35 arm e, lever H, link J, post I, and wire 5 to post N, thence to line. In practice a number of these devices are arranged upon a circuit containing an alarm apparatus of any preferred construction adapted to be operated by 40 a slight current, such as a mechanically-operated bell controlled by an electro-magnet, and are located at the various points where an unusual rise in temperature caused by a fire is liable to occur, as in mills or other places 45 where thermostats are usually placed.

50 Upon the breaking out of a fire near one of the devices or an unusual rise in temperature from other causes the solder on the link J will be melted and the sections separated by 55 the force of spring G, acting through the armature-shaft, arm e, and lever H, allowing the armature to rotate rapidly for a few turns. This will sever the circuit through the link and the rapid rotation of the armature will 60 generate a current therein, which will pass out over the line through the circuit embodying the fusible joints of the other instruments

and operate the alarm apparatus wherever it may be. The path traversed by the current from the generator, it will be noted, is of comparatively low resistance, passing through the fusible joint-circuit and not through the coils of the armature of each instrument, so that even should the fusible joint-circuit of one or two of the instruments be broken by accident 70 or by reason of a fire any other in the circuit could operate the alarm apparatus.

75 The herein-described instrument could be applied to many uses, such as operating a valve - operating mechanism for "dry-pipe" 80 fire-extinguishing systems or similar purposes.

85 Of course the fusible link could be connected directly with the arm on the armature, if desired, instead of through the lever; but I prefer the arrangement shown, as there is not so much strain upon it; consequently it is not so liable to be accidentally broken.

90 Various modifications will at once suggest themselves to those skilled in the art, and I therefore do not desire to be confined to the precise details shown.

I claim as my invention—

1. The combination, with a magneto-generator embodying a field-magnet and an armature adapted to be rotated, of a motor for rotating said armature, a stop for holding it in check, and a joint embodying a readily-fusible material for holding said stop in position, 95 substantially as described.

2. The combination, with a magneto-generator embodying a field-magnet and an armature adapted to be rotated, of a spring-motor for rotating said armature, a stop for holding it in check, and a joint embodying readily-fusible material for retaining said stop in position, 100 substantially as described.

3. The combination, with a magneto-generator embodying a field-magnet and an armature adapted to be rotated, of a motor for rotating said armature, a lever co-operating with 105 the armature to hold it in check, and a link embodying readily-fusible material for holding the lever in engagement, substantially as described.

4. The combination, with a magneto-generator embodying a field-magnet and an armature adapted to be rotated, of a motor for rotating said armature, a stop engaging the armature, a joint embodying readily-fusible material for holding the stop in engagement, a 110 circuit embodying the armature-coils, and a circuit embodying the fusible connection, substantially as described.

5. The combination, with a magneto-generator embodying a field-magnet and an armature adapted to be rotated, of a motor for rotating said armature, a stop engaging said armature, a joint embodying readily-fusible material for holding the stop in engagement, electrical connections between the terminals of 115 the coils and through the fusible joint, substantially as described.

6. The combination, with a magneto-generator embodying a field-magnet and an armature

ture adapted to be rotated, of a motor for rotating said armature, a stop engaging said armature, a joint embodying readily-fusible material for holding the stop in engagement, one terminal of the coils connected to the armature, and electrical connections from the other terminal through the fusible joint, stop, and armature, substantially as described.

7. The combination, with a magneto-generator embodying a field-magnet and an armature, of a motor for rotating said armature, a projection on the armature, a lever engaging said projection having a slot therein, a projection having a corresponding slot, and a link adapted to connect them embodying readily-fusible material, substantially as described.

8. The combination, with a magneto-generator embodying a field-magnet, a movable ar-

mature, and a motor for operating it, of a readily-fusible connection for preventing said armature from moving until melted, and then allowing the motor to move it and generate a current, substantially as described.

9. The combination, with a magneto-generator embodying a field-magnet, a movable armature, and a motor for operating it, of a readily-fusible connection for preventing said armature from moving until melted, and then allowing the motor to move it and generate a current, a circuit embodying the coils of the generator, and a shunt controlled by the fusible connection, substantially as described.
